UNITED STATES PATENT OFFICE.

RICHARD PIKE, OF ST. JOHN'S, NEWFOUNDLAND.

PROPELLER.

Application filed December 10, 1921. Serial No. 521,978.

To all whom it may concern:

Be it known that I, RICHARD PIKE, a subject of the King of Great Britain, and a resident of St. John's, Newfoundland, have invented certain new and useful Improvements in Propellers, of which the following is a specification.

My invention relates to propellers, particularly for ships, and has for its object 10 to provide a device of this character which will combine great simplicity and strength with an efficiency considerably superior to that of ordinary screw-propellers. This result I obtain by a special novel arrangement 15 of propeller blades in pairs, the blades of the same pair being arranged one in front of the other in the peculiar manner set forth hereinafter, whereby the pressure of the water thrust backward by the forward blade will 20 be utilized in driving the rear blade.

Without desiring to restrict myself to the specific embodiment illustrated, I will now proceed to describe, as an example, the form 25 of my improved propeller shown in the accompanying drawing, in which Fig. 1 is a rear elevation of the propeller; Fig. 2 is a side elevation thereof, showing also the propeller shaft and the stern of the ship; Fig. 3 is a section substantially on line 3—3 of Fig. 1; Fig. 4 is a top view; and Fig. 5 is a diagrammatic developed view illustrating the distances between corresponding points 30 of the blades of the same pair, at the edges of such blades.

In Fig. 2, A indicates the stern of a ship, and B the propeller shaft, with an arrow showing the direction in which said shaft rotates normally, that is to say, during forward motion of the ship. On this shaft a hub C is secured in any suitable manner, and the blades are fastened to this hub in any appropriate way, or they might be made integral therewith. In the particular example 40 illustrated, I have shown four blades D, E, D', E', arranged in two pairs, D, E and D', E' respectively, the blades D, D' being the forward blades, that is, nearer the stern A, while the blades E, E' are the rear blades. As will be seen best by reference to Fig. 1, 45 one pair of blades is equidistant from the other pair, measured circumferentially, that is to say, when there are two pairs of blades, these pairs are 180° apart, and the spacing would be different, but still equal or uniform, 50 in case a greater number of pairs were used. While, as stated, the blades D, D' are 180°

apart, and a like relation obtains in regard to the blades E and E', the blades of the same pair are spaced or offset from each other circumferentially, so that one of them will be in advance, with reference to the direction of rotation indicated by the arrow in Fig. 1, and according to my invention, this leading blade is the rear blade E or E'. The two blades of the same pair are portions of a pair of similar or parallel threads or spirals, and owing to one blade (the rear blade) leading the other as set forth, said leading blade will overlap or cover part of the surface of the other blade (the following blade, or front blade), and according to my invention the amount of this overlapping is quite considerable, amounting to one half of the area of the blade, or more. It will be understood that each of the four blades is of the same character, that is, they are alike in pitch and in the form of their surfaces, and differ only in position. The longitudinal (radial) axes of the individual blades, therefore, all form the same angle (90° in the construction illustrated) with the axis of rotation. The overlapping referred to above is to be understood as indicating the appearance of the propeller to an observer looking along the axis of the propeller, from the rear, as in Fig. 1. There is also, as shown in Fig. 2, a certain amount of overlapping when the device is viewed from the side, or transversely of the axis, the distance between corresponding points of the blades of the same pair, measured along the axis of rotation, being about equal to half the width of the blades. The two rear blades E, E' are at the same distance from the end of the shaft B, that is, the centers of said rear blades rotate in the same plane; similarly, the centers of the two front blades D, D' rotate in the same plane, which plane of course is nearer the stern A, that is to say, in advance of the plane in which the centers of the blades E, E' rotate.

Fig. 5 illustrates, in a developed view, the distances between like points along the edges of the two blades of the same pair, and for the purpose of greater clearness, similar points along such edges have been designated by like letters in Figs. 2 and 5. Owing to the shape of the blades, this distance is least at the inner portions of roots of the blades, and greatest at the outer portions or tips, where the blade edges are farthest from the axis of rotation.

A propeller constructed according to my invention, whether in the exact form illustrated or in other embodiments, is greatly superior to the usual screw propellers, and, 5 in particular, offers the following important advantages: There is a remarkable decrease in vibration, and therefore a very steady running of the propeller and of the ship. There is also found (probably as the result 10 of such steady running) a great lowering of fuel consumption for the same speed of the ship, and an increase in speed of from 5 to 10%, with the same engine power. This improved operation of my propeller is due 15 chiefly, I believe, to the highly advantageous relative location of the two blades of the same pair. With the arrangement described, the forward blade will, during the normal or forward travel of the ship, thrust the water 20 backward against the adjacent rear blade, which, as stated, is the leading blade in that case, and the energy of this flow of water is thus utilized in driving the rear blade.

The normally active or front surface, and, 25 the normally inactive or rear surface of a blade (which latter surface becomes active when the propeller is reversed), may be of substantially similar character, as illustrated by Fig. 3.

While I have referred to my improved propeller as applied to the propulsion of water-craft (boats, ships, submarines, torpedoes, etc.), it may be used for the propulsion of air-craft as well. In special cases, 30 a device of the character described might be used as a pump or a fan, or the device might be employed as a motor operated by a current of water, air, or other fluid. The blades preferably increase in width from their roots 35 outwardly to a certain point, and then again decrease in width (measured circumferentially) gradually to their tips, but I desire it to be understood that various modifications may be made without departing from 40 the nature of my invention as set forth in 45 the appended claims.

I claim as my invention:

1. A device adapted for use as a propeller, 50 consisting of a rotary structure comprising a hub and pairs of blades extending therefrom, said pairs being spaced equidistant

circumferentially, the two blades of the same pair forming portions of similar spirals and being offset along the axis of rotation by about half the width of said blades, so that one blade will be in front of the other, the longitudinal axes of all the blades forming the same angle with the axis of rotation, the rear blades having their corresponding points in the same planes perpendicular to 55 said axis, and the front blades likewise having their corresponding points in the same planes perpendicular to said axis, the rear blade of each pair being offset circumferentially relatively to the front blade of the same pair and, when viewed in a direction along the axis of rotation, overlapping such front blade by at least one-half of its area, the circumferential offset being in such direction that such rear blade will be the leading blade, during the rotation of the device 60 in the normal direction, to secure an efficient consecutive contact of the fluid with the two blades of the same pair.

2. A device adapted for use as a propeller, 75 consisting of a rotary structure comprising pairs of blades which pairs are spaced evenly in a circumferential direction, the two blades of the same pair being offset from each other both circumferentially and lengthwise of the 80 axis of rotation, and overlapping both when viewed along said axis and at right angles thereto, the direction of circumferential offset being such that when the device is rotating in the normal direction, the rear blade of 85 each pair will be the leading blade.

3. A device adapted for use as a propeller, 90 consisting of a rotary structure comprising pairs of blades which pairs are spaced evenly in a circumferential direction, the longitudinal axes of all the blades being perpendicular to the axis of rotation, and the two blades of the same pair being offset from each other both lengthwise of the axis of 95 rotation and circumferentially, the direction of circumferential offset being such that when the device is rotating in the normal direction, the rear blade of each pair will be the leading blade.

In testimony whereof I have signed this 100 specification.

RICHARD PIKE.
